UNITED STATES PATENT OFFICE.

WILLIAM H. PERRY, OF CONCORD, NEW HAMPSHIRE.

DESIGN FOR A MONUMENT.

SPECIFICATION forming part of Design No. 21,451, dated April 5, 1892.

Application filed March 3, 1892. Serial No. 423,674. Term of patent 3½ years.

To all whom it may concern:

Be it known that I, WILLIAM H. PERRY, a citizen of the United States, residing at Concord, in the county of Merrimac and State of New Hampshire, have invented and produced a certain new and original Design for Monuments, of which the following is a specification.

In the accompanying drawing letters and figures of reference will be used to designate the various features of my design.

The base (shown at 1) has four vertical sides, which terminate at its top in an obtuse frustum 2 of a pyramid. The pedestal 3 has four vertical sides joining at their bottom the frustum 2, and terminates at its top in an acute frustum of a pyramid, (seen at 4,) one or more sides of which may be provided with a raised tablet 5. The shaft 6 has four vertical sides, which terminate at their top in a four-sided cone 7. Said shaft is ornamented on each of its sides by the tablets 8, 9, and 10, the tablets 8 and 10 being raised, the top edge of the former and the bottom edge of the lat-

ter being chamfered down to said shaft-level, 25 as seen at 11, and the said raised tablets 8 and 10 are each ornamented by a V-groove 12, and each of the four sides of the cone 7 may be ornamented by a tablet 13.

In my design a special feature of ornamentation is produced by surfaces of a different character, which are denoted by letters of reference—viz., A B C. The surfaces, shown at A represent rock-work—*i. e.*, the surface is left as nearly as possible just as split. The 35 surfaces at B represent hammered work, while the surfaces marked C denote polished work.

Having described my design, what I claim is—

The design for a monument, as herein shown and described.

In testimony whereof I affix my signature in presence of two witnesses.

WILLIAM H. PERRY.

Witnesses:

J. B. THURSTON,
CARRIE E. EVANS.
